(57) **CLAIM**

The ornamental design for a cup holder, as shown and described.

DESCRIPTION

FIG. 1 is an isometric view of the cup holder having an oval shaped bezel viewed from the front right thereof;

FIG. 2 is a plan view of the cup holder;

FIG. 3 is a bottom view of the cup holder;

FIG. 4 is a front view of the cup holder;

FIG. 5 is a rear view of the cup holder;

FIG. 6 is a side view of the cup holder; and,

FIG. 7 is a view of an alternate embodiment of the cup holder wherein the bezel is rectangular in configuration rather than oval as in the embodiments of FIGS. 1-6.

The broken lines are for illustrative purposes only and form no part of the claimed design.
